UNITED STATES PATENT OFFICE.

DE WATT PEPPER, OF NEW MILFORD, CONNECTICUT.

DESIGN FOR A DIVAN-FRAME.

SPECIFICATION forming part of Design No. 36,202, dated January 27, 1903.

Application filed December 26, 1902. Serial No. 136,749. Term of patent 3½ years.

To all whom it may concern:

Be it known that I, DE WATT PEPPER, a citizen of the United States, residing at New Milford, in the county of Litchfield and State of Connecticut, have invented and produced a new, original, and ornamental Design for a Divan-Frame; and I do hereby declare the following to be a full, clear, and exact description of the invention, such as will enable others skilled in the art to which it appertains to make and use the same.

The accompanying drawing shows a front elevation of my new design.

As shown in the drawing, the leading or material features of my design consist of a perfectly plain horizontally-disposed back rail 1, perfectly plain horizontally-disposed side rails 2, the front columns 3 at the ends of the divan, upon which columns the rails 2 rest, said columns having at their upper ends acanthus-like ornamentations 4, vertically

disposed and extending in opposite directions, the single leaf-like ornamentations 5, vertically disposed above the ornamentations 4, said columns throughout their main lengths being rounded in cross-section, and the feet 6, circular in vertical section, the curvature of said feet extending in a plane at right angles to the plane of the curvature of the body portions of the columns 3.

Having thus described my invention, what I claim as new, and desire to secure by Letters Patent, is—

The ornamental design for a divan-frame, as herein shown and described.

In testimony whereof I affix my signature in presence of two witnesses.

DE WATT PEPPER.
